UNITED STATES PATENT OFFICE

2,131,133

HOISTING DEVICE

Henry B. Babson, Chicago, Ill., assignor to Babson Bros., a corporation of Illinois

Application July 28, 1937, Serial No. 156,225

2 Claims. (Cl. 212—49)

This invention relates to a hoisting device and more particularly to a swingably mounted hoisting device suitable for lifting heavy articles into a conveyance.

5 The invention is illustrated in the drawing, in which Fig. 1 is a vertical elevation, partly in section, of the device, and Fig. 2 is a similar view of the device mounted at the rear end of the conveyance. Figure 3 is an elevation of the winch illustrating the wrapping of the rope thereabout.

In lifting heavy articles into trucks or other conveyances, it is desirable to have a pivotally mounted member carrying the weight, and at the same time it frequently becomes necessary 10 to raise or lower the article being lifted, a short distance. It is inconvenient and often impossible to return to the main lifting device for this purpose.

In accordance with the present invention a 20 device is provided which makes it easily possible to lower a weight by any desired distance simply by lifting a much smaller weight the same distance, and at the same time the weight will then be held at the adjusted position without further 25 operation.

The device comprises a davit member 10 preferably of metal and hollow at its lower portion as indicated at 11. The davit member is rotatably mounted at its base, for example in the 30 collar 12, which may be mounted upon or adjacent to the rear platform 13 of a truck 14. Carried intermediately of the davit is a winch 15 provided with a lever handle 16 operating on the customary ratchet mechanism 17 whereby the 35 winch is held against movement in one direction. Near the outer end of the davit is a pulley 18 carried by the pintle 19 and the frame 20. Intermediately of the davit is a second pulley 21 carried by pintle 22 and frame 23. A flexible hoisting member such as a rope 24 passes over the 40 pulley 18 several times, around the winch 15, over the pulley 21 and is fastened within the hollow portion of the davit to a weight 25. The loose end of the rope is of course attached to any 45 suitable object to be lifted such as a carton or can of milk 26.

The weight 25 may be very light, only being sufficient in amount to maintain the rope 24 in tension upon the winch 15. For normal purposes 50 a weight of 5 lbs. is ample in connection with the strength of rope ordinarily required to lift a can of milk weighing say 125 lbs.

In operation of the device the rope is fastened to an object to be lifted, and the article 55 is then lifted by operation of the hand lever 16 until the object has cleared the platform of the

truck. The davit may then be swung inwardly and the weight lowered simply by pulling on the rope 24 at the point marked 27 any desired distance. This operation removes the tension of the weight 25 from the winch and permits the rope to slip from the smooth winch, thereby 5 lowering the object the same distance.

It is obvious that where the distance within the davit is not great enough to permit lifting of the weight the desired amount, a block and tackle arrangement may be employed to cut down 10 the movement of the weight 25, but in such case the mass of the weight will have to be increased accordingly.

The weight 25 is in no sense a counter-weight, 15 being sufficient only to hold the tension upon the winch 15. Ordinarily 3 or 4 turns of the rope about the winch will suffice.

Obviously any flexible member other than the ordinary vegetable fibre rope may be employed, 20 but ordinary rope is preferred. Likewise the term "pulley" has been used to cover similar slide members.

The foregoing description has been given for 25 clearness of understanding only, and no unnecessary limitations should be understood therefrom, but the appended claims should be construed as broadly as permissible in view of the prior art.

What I claim as new, and desire to secure by Letters Patent is:

1. In a lifting device, a winch, means for preventing movement of the winch in one direction, a rope wrapped about the winch a few turns and held thereon substantially solely by its frictional engagement therewith, one end of said rope being adapted to be attached to a relatively heavy object to be lifted, and the other end attached to a relatively small weight holding the rope in frictional engagement with the winch, the number of turns of rope upon the winch being large enough to maintain proper friction, and small enough 40 that upon release of the small weight, the frictional engagement thereof will be released.

2. In a conveyance, a platform, a davit member rotatably mounted upon the platform having an elongated hollow portion, a pulley carried by 45 the davit near the outer end thereof, a winch associated with the davit, a small hand-movable weight within the hollow portion of the davit, a rope connected to the weight, wrapped several times about the winch and passing through the 50 pulley and adapted for attachment to a relatively large weight, and means for preventing movement of the winch in one direction.
